UNITED STATES PATENT OFFICE

2,350,660

DRILL STEEL CENTRALIZER

John C. Curtis, Claremont, N. H., assignor to Sullivan Machinery Company, a corporation of Massachusetts

Application October 22, 1942, Serial No. 462,931

18 Claims. (Cl. 255—51)

This invention relates to rock drills, and more particularly to a centralizer for the drill steel of a rock drill of the mounted type.

In rock drills of the mounted type the drilling motor which percussively actuates the drill steel is usually mounted on a guide suitably supported with respect to the work. There is usually provided at the forward end of the guide a centralizer for centering the drill steel during starting or "spotting" of a drill hole. As the drilling motor is fed along the guide-guideways and approaches the drill steel centralizer, the centralizer is usually automatically released from the steel and moved into its non-guiding position so that the drilling motor may be fed along the guide-guideways forwardly past the centralizer. In such drills, it is also desirable to effect automatic release of the drill steel centralizer as the drilling motor is fed rearwardly subsequently to the starting of a drill hole with a relatively short starting steel, so that as the drill bit which is of larger diameter than the drill steel body approaches a centralizer, the latter is automatically moved out of guiding relation with its drill steel, thereby to permit the drill bit to move rearwardly past the same. Thus in such rock drills, it is desirable to effect automatic movement of the drill steel centralizer into its released non-guiding position during either forward or rearward movement of the drilling tool along the guideways of its guide.

It is accordingly an object of the present invention to provide a novel drill steel centralizer which embodies the desired characteristics as above outlined in that not only is the centralizer automatically moved into released position during forward feed of the drilling tool, but is also automatically moved into its released position during reverse feed of the drilling tool. Another object is to provide an improved drill centralizer having novel means for effecting automatic release of the same as the drilling tool is fed along its guide. A further object is to provide an improved drill steel centralizer having novel mounting means for the centralizer elements thereof. Still another object is to provide an improved drill steel centralizer which is automatically moved into its released non-guiding position upon bodily movement of the centralizer elements thereof in a direction opposite to that in which the drilling tool is being fed and having novel releasing means for the centralizer elements actuated directly by engagement therewith of a part of the drilling tool. Still another object is to provide an improved drill steel centralizer wherein the drilling tool as it is fed forwardly along the guide-

guideways effects, through novel operating means, bodily movement of the centralizer elements in a rearward direction, thereby to effect automatic release of the centralizer as the drilling tool approaches the same. A still further object is to provide an improved drill steel centralizer which is automatically released from its steel guiding position directly by engagement with the drill bit therewith as the drilling tool is fed rearwardly along its guide. With these and other objects in view, this invention relates to novel features of construction, operation and arrangement of parts, one embodiment of which is given in the specification and illustrated in the accompanying drawing, wherein:

Fig. 1 is a side elevational view of the forward portion of a rock drill with which an illustrative embodiment of the improved drill steel centralizer is associated.

Fig. 2 is a front end elevational view of the rock drill and steel centralizer shown in Fig. 1, with the drill steel shown in cross section.

Fig. 3 is a view in longitudinal vertical section taken substantially on line 3—3 of Fig. 2.

Fig. 4 is a cross sectional view taken substantially on line 4—4 of Fig. 1, showing the centralizer arms in steel guiding position.

Fig. 5 is a cross sectional view taken substantially on line 5—5 of Fig. 1, showing the steel centralizer arms in released non-guiding position.

Fig. 6 is a cross sectional view taken substantially on line 6—6 of Fig. 3.

In this illustrative embodiment of the invention the improved drill steel centralizer, generally designated 1, is shown associated with a conventional rock drill of the mounted drifter type. It will be evident, however, that the improved centralizer may be associated with other types of rock drills, as for instance, a wagon drill.

The rock drill disclosed herein comprises a conventional drilling tool embodying a drilling motor 2 mounted on a usual guide 3 for movement toward and from the work. The drilling motor is of the well known pressure fluid actuated hammer type having a motor cylinder 4 containing a reciprocable hammer piston (not shown) for percussively actuating the drill steel 5 suitably attached in a usual chuck within a front chuck housing 6 in turn suitably secured to the front end of the motor cylinder. The drill steel 5 carries at its front end a usual detachable drill bit 7. The motor cylinder has usual lateral guides 8 slidably received in longitudinal guideways 9 of the guide 3. The drilling tool may be fed in a well

known manner along the guideways of the guide 3 toward and from the work by means of a conventional feed screw 10 journaled on the guide and engageable with a non-rotatable feed nut (not shown) carried by the drilling motor so that when the feed screw is rotated, the drilling tool is fed along the guide-guideways. Since, as above stated, the rock drill is of a conventional design and is well known to those skilled in the art, further disclosure thereof is herein unnecessary.

Now referring to the improved drill steel centralizer 1, it will be observed that attached by bolts 12, herein preferably three in number, to the front end of the guide 3 are parallel front and rear transverse plates 13 and 14 held in proper spaced relation by spacing sleeves 15 surrounding the bolts between the plates. The rear plate 14 has an integral bearing boss 16 in which a front bearing portion 17 of the feed screw 10 is journaled as shown in Fig. 3. Pivotally mounted on the spacing sleeves of the upper pair of bolts between the plates is a pair of cooperating centralizer arms 18, 18 each having an appropriately shaped guiding portion 19 for engaging the body of the drill steel 5. The guiding portions of the centralizer arms when the latter are in their closed position, as shown in Fig. 4, embrace the body of the drill steel to hold the latter centered during starting or "spotting" of a drill hole in a manner well known to those skilled in the art.

As shown in the drawing, the centralizer arms are also mounted on the upper pair of spacing sleeves for bodily, herein translatory, sliding movement relative thereto in a longitudinal direction between the plates, and the arms have near their pivots downwardly projecting lockings lugs 20 engageable when the arms are in their foremost guiding position, with opposite vertical side surfaces 21 on the front plate 13. A torsion spring 22, common to both centralizer arms, has coil portions 23 encircling the upper spacing sleeves at the arm pivots, and these coil portions are arranged between the rear surface of the arm hubs and the front face of the rear plate and serve to urge the arms forwardly against the front plate. The coil portions are connected together by a cross portion 24 extending between the arms, and the end portions of the spring are attached at 25 to the inner sides of the arms. This torsion spring not only urges the centralizer arms forwardly into their locked position against the front plate 13 with the locking lugs 20 in engagement with the vertical side surfaces 21, but also serves automatically to move the centralizer arms about their pivots when the locking means is released. The locking lugs 20 on the arms, as the latter are swung apart into the position shown in Fig. 5, engage abutment surfaces 26 on the front plate, thereby to limit outward swinging of the arms.

In the novel construction for effecting rearward bodily movement of the centralizer arms into a position to release the locking lugs 20 from engagement with the front plate surfaces 21, there is provided a lever 27 pivoted at 28 on the forward end of the guide 3 in adjacency to the rear plate 14, and this lever extends through openings 29 and 30 in the guide 3 and rear plate 14 respectively, as shown in Fig. 3. This lever has at its rear end a yoke-shaped actuating portion 31 which straddles the feed screw 10 (Fig. 6). The forward end of this lever has a cam portion 32 engageable with pins 33 fixed to the arm lugs 20. The chuck housing 6 of the drill-

ing motor has depending lugs 34 engageable with the arms of the lever yoke 31 for swinging the lever about its pivot as the drilling tool moves forwardly along the guide-guideways and approaches the steel centralizer. A coil spring 35 encircling the lever pivot serves to urge the lever into its raised operative position shown in Fig. 3. When the rearward portion of the lever is depressed by the chuck housing lugs, the cam portion 32 is moved upwardly, and the inclined surface of the cam engaging the arm pins 33 moves the centralizer arms bodily rearwardly toward the rear plate, thereby automatically to release the arm locking means from the front plate 13 as the drilling tool is fed forwardly along the guide-guideways toward the centralizer. The drill bit 7 has a rear abutment surface 36 engageable with the guiding portions 19 of the centralizer arms so that when the drilling tool is fed rearwardly along the guide-guideways, the arms are moved bodily rearwardly out of locking engagement with the front plate 13. When the locking means is released the torsion spring 22 acts to throw the centralizer arms into their wide open position so that upon continued rearward movement of the drilling tool the drill bit may move rearwardly past the same.

The mode of operation of the improved drill steel centralizer will be clearly apparent from the description given. When it is desired to start or "spot" a drill hole the centralizer arms 18 may be manually swung about their pivots into their guiding position shown in Figs. 1 and 2 with the guiding portions 19 in engagement with the body of the drill steel and at that time, the arms are held locked in guiding position by engagement of the arm lugs 20 with the side surfaces 21 of the front plate 13. As the drilling tool is fed forwardly along the guide-guideways, the depending lugs 34 on the chuck housing engage the arms of the yoke 31 of the lever 27, thereby swinging the lever about its pivot into the position indicated in dotted lines in Fig. 1 to raise the cam portion 32 which engages the arm pins 33, to move the arms bodily rearwardly, thereby to effect release of the locking lugs from the front plate surfaces. When the arms are unlocked from the front plate, the torsion spring acts automatically to throw the centralizer arms into the wide open non-guiding position shown in Fig. 5, so that the drilling tool may continue to move forwardly between the arms past the centralizer. As the drilling motor is fed rearwardly along the guide-guideways subsequently to the "spotting" of the drill hole with a relatively short starting steel, the surface 36 on the drill bit abuts the guiding portions of the centralizer arms, thereby to effect bodily movement thereof rearwardly to release the arm locking lugs from the front plate, and when the locking lugs are released the arms are automatically thrown apart into their wide open non-guiding position by the torsion spring. It is accordingly evident that irrespective of the direction of movement of the drilling tool along the guide-guideways, the centralizer is automatically released from the drill steel, thereby to prevent accidental engagement of the chuck housing or the drill bit with the centralizer arms when the latter are held closed which might result in damage to the drill. When the centralizer arms are in their wide open position shown in Fig. 5 and it is desired to position the guide arms in guiding relation with the drill steel, the operator may manually swing the arms

against the tension of the torsion spring 22 into engagement with the drill steel and thereafter may shove the guide arms bodily forwardly into locking engagement with the front plate 13. When the centralizer arms are moved into their closed guiding position, the pins 33 thereon are brought into operative relation with respect to the cam portion of the operating lever 27.

As a result of this invention, it will be noted that an improved drill steel centralizer is provided which is automatically moved into its released non-guiding position and the drilling tool assumes predetermined positions as it is fed either forwardly or rearwardly along the guideways of its guide. It will further be evident that by mounting the centralizer arms so that they move rearwardly out of their locked position, the centralizer may be automatically released from the drill steel by engagement of the drill bit with the guide arms. It will further be evident that by the provision of the improved operating means the centralizer arms are automatically moved into their released non-guiding position in an extremely effective manner. Other uses and advantages of the improved drill steel centralizer will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a drill steel centralizer, a support, centralizer means mounted on said support to move translationally relative thereto into and out of steel guiding position, and means movably mounted on said support and engaging said centralizer means for effecting rearward translatory movement of the latter with respect to the drill steel out of steel guiding position.

2. In a drill steel centralizer, a support, a pair of relatively movable, swingable centralizer arms mounted on said support for translatory movement into and out of steel guiding position, and means movably mounted on said support and engageable with said arms for effecting rearward translatory movement of the latter with respect to the drill steel into a position to permit relative swinging of said arms out of steel guiding position.

3. In a rock drill, a guide providing guideways, a drilling tool for actuating a drill steel and movable back and forth along said guide-guideways, a drill steel centralizer mounted on said guide for centering the drill steel, and means automatically operative as said drilling tool moves rearwardly along said guide-guideways for effecting release of said centralizer from the steel.

4. In a rock drill, a guide providing guideways, a drilling motor for actuating a drill steel and movable back and forth along said guide-guideways, a drill steel centralizer mounted on said guide for centering the drill steel and including centralizer means mounted for translatory movement into and out of steel engaging position, and means operated by said drilling motor as the latter moves forwardly along said guide for effecting rearward translatory movement of

said centralizer means toward its released position.

5. In a drill steel centralizer, a support, drill steel centralizer means mounted on said support and movable translationally relative thereto toward its released position, and a lever on said support for translationally moving said centralizer means toward released position.

6. In a rock drill, a guide, a drilling tool for actuating a drill steel and movable back and forth along said guide, a drill steel centralizer on said guide for centering the drill steel, and means for effecting automatic release of said centralizer from said steel when said drilling tool assumes a predetermined position on said guide during movement thereof in one direction along said guide and also when said drilling tool assumes a predetermined position during the opposite movement thereof.

7. In a rock drill, a guide, a drilling motor for actuating a drill steel and movable forwardly along said guide toward the work, a drill steel centralizer mounted on said guide for centering the drill steel, said centralizer including centralizer means movable rearwardly with respect to said guide towards its released non-guiding position, and means operated by said motor as it approaches said centralizer for effecting rearward movement of said centralizer means.

8. In a drill steel centralizer, a support, a pair of centralizer arms mounted on said support for pivotal and translatory movements and having steel engaging portions, and means on said support and engaging said arms near their pivots at the sides of the latter remote from said steel engaging portions for effecting translatory movement thereof.

9. In a drill steel centralizer, a support, a pair of relatively movable centralizer arms mounted on said support for translatory and pivotal movements, locking means for holding said arms against pivotal movement and releasable upon translatory movement of said arms into a predetermined position, and lever mechanism on said support for translationally moving said arms.

10. In a drill steel centralizer, a support, a pair of centralizer arms mounted on said support for pivotal and translatory movements and having steel engaging portions, locking means for holding said arms against pivotal movement and releasable upon a predetermined translatory movement of said arms, and means on said support operatively engageable with said arms near the pivotal axes thereof at the sides of said pivotal axes remote from said steel engaging portions for translationally moving said arms.

11. In a rock drill, a guide, a drilling tool for actuating a drill steel and movable along said guide, a drill steel centralizer mounted on said guide for centering the drill steel, said centralizer embodying a locking element movable rearwardly to effect release of said centralizer from the drill steel, and means operated by said drilling tool as the latter moves forwardly along said guide for effecting rearward movement of said locking element.

12. In a rock drill, a guide, a drilling tool for actuating a drill steel which carries a drill bit, said tool being movable back and forth along said guide, a drill steel centralizer on said guide for centering the drill steel, and means for locking said centralizer in guiding position and automatically releasable upon engagement of said

drill bit therewith as said drilling tool moves rearwardly along said guide.

13. In a rock drill, a support adapted to support a drilling tool for feeding movement therewith, centralizer means mounted on said support to move translationally relative thereto into and out of tool guiding position, and means actuated by the drilling tool for effecting translatory movement of said centralizer means, said last mentioned means including an operating member mounted on said support for movement relative thereto and to said centralizer means, said operating member moving said centralizer means translationally and having a portion projecting into the path of tool movement.

14. In a rock drill, a support adapted to support a drill steel actuator for movement therewith, centralizer means mounted on said support to move translationally relative thereto into and out of steel guiding position, and means mounted on said support for movement with respect to the drill steel actuator and to said centralizer means for translationally moving said centralizer means.

15. In a rock drill, a support adapted to support a drill steel actuator for movement therewith, centralizer means mounted on said support to move translationally relative thereto into and out of steel guiding position, and means mounted on said support for movement with respect to said steel actuator and said centralizer means, and engaging said centralizer means at points remote from the steel engaging portions thereof for translationally moving said centralizer means.

16. In a drill steel centralizer, a support, centralizer means mounted on said support to move into and out of steel guiding position, means for locking said centralizer means in steel guiding position, and means movably mounted on said support and engaging said centralizer means for effecting rearward translatory movement of said centralizer means relative to said support to effect release of said locking means.

17. In a rock drill, a guide along which a drill steel actuator is guided for movement, centralizer means mounted at the front end of said guide to move into and out of steel guiding position, means for locking said centralizer means in steel guiding position, and means movably mounted on said guide and having a portion projecting into the path of movement of said steel actuator for actuation by the latter, said last mentioned means upon actuation thereof effecting rearward translatory movement of said centralizer means relative to said guide to effect release of said locking means.

18. In a drill steel centralizer, a support, a pair of guide arms pivotally mounted on said support to swing relative thereto about spaced apart parallel axes, said arms being movable translationally relative to said support during their movement out of their steel guiding position, and an actuator element movably mounted on said support and projecting into the space between the arm pivot axes for translationally moving said arms.

JOHN C. CURTIS.
